VICTOR H. HARBERT, OF CHICAGO, ILLINOIS, ASSIGNOR TO ILLINOIS RAILWAY EQUIPMENT COMPANY, A CORPORATION OF ILLINOIS

CLAMP FOR PIPES

Application filed March 12, 1928. Serial No. 261,101.

My invention relates to means more especially intended for clamping and firmly holding the air pipes of air brake systems in place and especially means for properly securing the air pipes disposed longitudinally beneath a railroad car for holding the same against vibration and movement.

The invention contemplates means composed of a few parts or members of simple construction, which may be easily and quickly applied to the air pipe and to an element or suitable portion of the car underframe through which the air pipes are usually disposed.

The construction and its application will be readily comprehended from the detailed description of the accompanying drawing, wherein—

Figure 1 is a plan view of my improved means applied to a portion of pipe and an element or cross member of the car underframe which is shown in section.

Figure 2 is a perspective view of one of the complementary members of the clamp.

Figure 3 is a perspective view of the other complementary member of the clamp.

Figure 4 is a side elevation illustrating a modified form of my improved clamp in its application to the car underframe, a portion whereof is shown in section, together with a portion of the pipe.

In the particular exemplification of the invention as disclosed in Figure 1, 10 illustrates a portion of the air pipe or line which constitutes a part of the air brake system of a railroad car. The invention is shown in its especial adaptation to the pipe which is disposed longitudinally beneath the car. In present railroad practice, these air pipes in most instances are made to pass through suitable apertures or openings in the diaphragms of the transversely disposed members of the car underframe; a portion of such transverse portion of the car underframe being indicated at

11 provided with an opening therethrough at 12 through which the air pipe 10 passes.

In order to prevent improper movement of the air line or pipe, which would result from the severe shocks or jars encountered by railroad cars in operation and to prevent improper chatter and vibration, I have provided clamping means comprising the substantially semi-cylindrical lower member 13 shown in Figure 2 formed to provide a suitable seat for the air pipe or line; with the lower outer surface of the member 13 provided with a pair of spaced and transversely disposed arcuate ribs 14. As the member 13 is intended to be disposed through the aperture 12 in the car underframe element 11, the ribs 14 are spaced apart a distance sufficient to receive the diaphragm or web portion 11 of the car underframe therebetween, with the result that when all of the elements have been properly assembled, longitudinal movement of member 13 will be impossible because of the straddling relation between the ribs 14 and the diaphragm or web portion 11 of the car underframe.

One end of member 13 is provided with a laterally disposed lug or arm 15 which is preferably slotted as at 16 for the purpose of receiving a suitable bolt 17. One side of the lug or arm 15 is shown provided with shoulders or lugs 18, 18 adapted to provide abutment for the head 19 of the bolt and thereby prevent its rotation; the shoulders 18 being adapted to engage one of the flat faces or sides of the bolt as shown in Figure 1.

After member 13 has been inserted through the aperture 12 in the car underframe element 11 in the manner described and the pipe 10 has been seated therein, the clamp member 20 shown in Figure 3 is then put into place longitudinally of the side of the pipe opposite to that on which member 13 is located. Member 20 consists of a substantially semi-cylindrical element, preferably of length some-

what greater than element 13 and adapted to partially encircle the pipe without, however, having its longitudinal edges contact with the longitudinal edges of member 13. The member 20 is preferably made of increasing thickness toward one end; that is to say the outer side of the member has a gradually upwardly sloping surface toward the end provided with the laterally disposed arm or lug 21 which latter is adapted, when the members are properly assembled, to be disposed parallel with arm 15 of member 13. Arm 21 is provided with a bolt receiving hole or aperture 22 through which bolt 17 is adapted to pass. Member 20 is intended to be disposed lengthwise of the air pipe or line 10 like member 13 and is intended to pass through the opening 12 in the car underframe member 11.

With member 20 made somewhat longer than member 13, it is apparent that the end having arm 21 will be disposed somewhat beyond the end of member 13 having arm 15 and therefore will be disposed a distance farther removed from the car underframe member 11. As member 13 will be held against longitudinal movement by the spaced lips 14, 14 which interlock with the car underframe member 11, it is evident when bolt 17 has been disposed through the apertures in arms 15 and 21, respectively, that screwing up of the nut 23 will cause member 20 to be drawn toward the car underframe member 11.

With the member 20 provided with a tapered surface, namely with a surface increasing in thickness toward the end having arm 21, it is apparent that a firm wedging relation with the car underframe member 11 will be provided and as a result the various elements of the clamp and the air pipe or line will be firmly wedged in place in the aperture in the car underframe and movement or vibration of the pipe or line made impossible.

In Figure 4 I illustrate a modification of the invention, in that the one or bottom member 24 is substantially similar to member 13, except that it is not provided with the laterally disposed lug or arm 15; member 24, however, having the spaced circumferentially disposed ribs 25, 25 similar to ribs 14, 14 intended to straddle opposite sides of the car underframe element 11.

Member 26 is substantially identical with member 20, except that in this modification I prefer to have the arm 27 extend laterally upward as shown in Figure 4 and substantially parallel with the underframe member 11, which latter in addition to the pipe receiving opening 12 therethrough is also provided with a bolt receiving opening 28 adapted to receive the bolt 29 which passes through the aperture 30 in the arm 27 of member 26. Member 26, like member 20, is provided with an outer tapered surface; that is to say member 26 preferably increases in thickness to-

wards the end provided with the arm 27. It is obvious from the construction shown in Figure 4 that when bolt 29 has been inserted through the diaphragm 11 of the car underframe member and the arm 27 and nut 31 is screwed up tightly on the bolt, member 26 will be forced lengthwise of the pipe 10, namely in a direction moving the arm 27 of the member toward the car underframe element 11, thus firmly wedging the various elements in place by reason of the tapered surface on member 26, causing the pipe 10 to be rigidly clamped between the members 24 and 26 and member 24 in turn firmly held in place, with the result that improper or longitudinal movement of the air pipe will be impossible.

The specification describes the specific exemplifications of my invention, which may, however, have expression in modified form without departing from the spirit of my invention.

What I claim is:

1. In combination with an apertured car under-frame member through which the pipe extends, a channeled pipe receiving member, the outer face whereof is arranged to provide interlocking engagement with the frame member, said member at one end being provided with a laterally disposed arm having an open-ended slot, a wedge member, one face whereof is adapted to receive the pipe, while the other face has a sloping surface, said wedge member at one end having a laterally disposed apertured arm and means adapted to be seated in the open-ended slot and in the aperture of the wedge member arm whereby said wedge member is forced lengthwise of the pipe and said sloping surface brought into wedging relation with the frame member.

2. In combination with an apertured car under-frame member through which the pipe extends, a channeled pipe receiving member whose outer surface is provided with spaced transversely disposed lugs adapted to straddle the underframe member, said member being provided with a laterally disposed arm, a wedge member whose inner face is adapted to fit about the pipe while the outer face has a sloping surface toward one end, said end being provided with a laterally disposed arm, and means adapted to engage with both arms whereby said wedge member is drawn lengthwise of the pipe into wedging relation with the underframe member.

3. In combination with an apertured car underframe member through which the pipe extends, a pair of complementary channel members, one of which has a transversely extending groove on its outer face adapted to receive the car underframe and provided at one end with a laterally disposed arm having a laterally disposed open-ended slot, while the outer surface of the other member

slopes toward one end whereof, said end being provided with a laterally disposed apertured arm, a bolt disposed through the slot and aperture of both arms, with the head of the bolt arranged adjacent to the arm with the open-ended slot, and a nut on said bolt for forcing said last mentioned member lengthwise of the pipe into wedging relation with the underframe, and means on the arm having the open-ended slot for preventing displacement of the bolt-head.

VICTOR H. HARBERT.
